(57) CLAIM

The ornamental design for portable partition, as shown and described.

DESCRIPTION

FIG. 1 is a perspective view of a portable partition, showing my new design;

FIG. 2 is a front view thereof;

FIG. 3 is a back view thereof;

FIG. 4 is a right side view thereof;

FIG. 5 is a left side view thereof;

FIG. 6 is a top plan view thereof; and,

FIG. 7 is a bottom plan view thereof.

The broken lines show portions of the portable partition that forms no part of the claimed design.

The portable partition can be used to separate a room.
